UNITED STATES PATENT OFFICE.

ROBERT OSTERHORN, OF ST. LOUIS, MISSOURI.

GUARD FENDER.

Application filed June 17, 1924. Serial No. 720,643.

To all whom it may concern:

Be it known that I, ROBERT OSTERHORN, a citizen of the United States, residing at St. Louis and State of Missouri, have invented certain new and useful Improvements in Guard Fenders, of which the following is a specification, reference being had to the accompanying drawings.

This invention relates to guard fenders 10 for attachment to self-propelled vehicles and more particularly to a front end guard fender adapted to completely protect the forward end of the vehicle against damage in collision.

15 An important object of the invention is to provide a device of this character so constructed that it will prevent injury to persons with which a vehicle to which it is applied may collide.

20 A further object of the invention is to provide a construction of this character which may be readily applied to vehicles without in any way altering the present construction thereof, being in the form of an 25 attachment.

A further object of the invention is the provision of a device of this character having a hinged swinging section adapted to contact with the legs of the person with 30 which the vehicle collides and which by its contact alters its position, tending to elevate the person engaged from the right-of-way to support them until the vehicle may be stopped.

35 A still further object of the invention is to provide a device of this character in which the cushioning of the shielding elements is so distributed as to make the fender most yieldable at those portions 40 which are most liable to contact with the bodies of persons collided with, so that injury to the vital portions is prevented.

These and other objects I attain by the construction shown in the accompanying 45 drawings, wherein for the purpose of illustration is shown a preferred embodiment of my invention and wherein:—

Figure 1 is a front elevation showing a combined guard fender and oscillator constructed in accordance with my invention 50 applied to a vehicle;

Figure 2 is a plan view thereof;

Figure 3 is a side elevation showing the construction of the lower portion of the 55 oscillator and guard;

Figure 4 is a detail rear elevation showing the mounting of the rollers;

Figure 5 is a detail view showing the joint of the crank;

Figure 6 is a detail view of the braces 60 employed for maintaining the bars of the oscillator in properly spaced relation.

Referring now more particularly to the drawings, the numeral 10 generally designates the side members of the frame of a 65 vehicle to which, in accordance with my invention, I rigidly attach the rear ends of supporting arms 11. These supporting arms are preferably channeled in their outer 70 faces and have their rear ends 12 conforming to the shaping of the side members of the frame which they abut. From these rear ends the arms incline downwardly and are offset from the body frame, as at 13, the forward ends thereof being arranged in 75 a plane forwardly of the front end of the frame and at a point considerably below the frame being provided with angular out-turned feet 14. To these outturned feet is secured a transversely disposed angle bar 80 15 having one flange thereof horizontally directed and the other flange thereof, which is secured to the transverse feet, upwardly directed. The arms 11, together with the 85 transverse bar 15, provide a support for the fender structure hereinafter described.

Secured to the transverse bar at the ends thereof extending upwardly therefrom are hollow square posts 16, the lower ends of which rest upon the horizontal flange of the 90 angle bar 15 and are secured to the vertical flange of the angle bar. The upper ends of these square bars are connected by an upper transverse bar. The upper ends of these 95 vertical bars, which extend to a height approximating the height of the top of the vehicle, are connected by a transverse bar 17 which is preferably held in position by means of angles 18, each having one arm secured to a vertical support 16 and the other arm thereof secured to the transverse bar 17. From the upper ends of the vertical bars 16 rearwardly extending braces 19 are preferably employed to connect the upper ends of these bars to the body of the 100 vehicle as shown. The upper bar 17 may be employed as a support for pennants 20 or the like if so desired. Secured to the lower ends of the vertical supporting posts 16 and to the angle bar 15 are the lower ends 105 110

of cross tie rods 21, the upper ends of which are connected with the supporting posts 16 adjacent the upper ends thereof to coil springs 22, which at the time of attachment are placed under tension so that these vertical posts are stiffened.

Secured at their lower ends to the vertical flange of the angle bar 15 at points uniformly spaced along the length thereof, intermediate the vertical supports 16, are a plurality of vertical metallic strips 23 the upper ends of which are connected to the upper cross bar 17 by coil springs 24, permitting inward movement of the upper ends of these strips under impact. With these strips 23 are interwoven a plurality of horizontal strips 25 which are formed of spring material and the ends of which are provided with forwardly looping bows 26 the ends of which are reverted and secured to the posts 16. By inspecting Figure 1 it will be seen that this structure provides a network supported from the front end of the vehicle and which is yieldably mounted, particularly as regards the upper end thereof, so that it will not present a rigid structure under impact. The rigidity of this structure is lessened at the upper end or those portions which would normally contact the head or the upper portions of the body of a person with which a vehicle to which it is applied might collide. This resiliency is further increased by increasing the size of the looped bows 26 at the ends of the transverse or horizontal strips 25 so as to thereby increase the resiliency thereof.

Secured to the lower surface of the horizontal flange of the angle bar 15 are a plurality of angle brackets 27 in which is mounted a shaft 28. To this shaft at points spaced thereon are attached three arms 29, two of these arms being so disposed that they operate adjacent the inner side faces of the vertical posts 16. These arms have each secured thereto at vertically spaced points a plurality of elliptic springs 30 which extend forwardly from the arms and are secured at opposite points to transversely extending bars 31 which may be made of wood or any other suitable material. In the present instance are disclosed three of the elliptic springs secured to each of the arms 29 and three bars being employed. It will be obvious that this number can be changed if desired. This spring is preferably formed of light readily yielding material in the form of a flat split elliptic band the ends of the arms of which are secured to the transverse strips 31 by means of carriage bolts as at 32. At the point of attachment of each set of the springs 30 to the bars, the bars are connected one with another by means of shackles 33 each in the form of a length of spring metal having a sinuous center section 34 and having at its ends eyes

receiving the carriage bolts forming the means of attaching the spring to the transverse bars. These shackles in normal operation will prevent relative movement of the bars but will permit separate movement 70 under impact so as to permit one bar to yield more than the remaining bars. The lowermost bar 31 has secured thereto, preferably by these same carriage bolts, roller mountings 35 in which are mounted rollers 36 projecting below the lower surface of the bar to elevate the bars as a unit upon contact with anything passing beneath the oscillator formed by the structure above described. The necessity for these rollers will be apparent when it is pointed out that the lowermost bar is preferably arranged slightly above the level of the ankle of the pedestrian and accordingly would be subject to contact with the road wheels of the vehicle 85 engaged in a rut or when the vehicle was passing along a sharply crowned road.

To the upper end of the two outermost arms 29 are secured ratchet links 37 each having a slot therein the upper surface of which is formed to provide forwardly facing ratchet teeth 38. The slots receive headed elements 39 which are secured to the posts 16, the headed element being normally engaged by the rear end wall of the slot. The rear extremities of these links are connected with the angle bar 15 by means of coil springs 40.

It will be noted that the arms 29 normally incline forwardly and upwardly and the plane, represented by the front faces of the transverse bars 31, is correspondingly inclined, so that upon contact of this oscillator with the body of a person, the uppermost bar is first engaged with the person. Because of the mounting of the arms permitting pivoting thereof and the yielding of the bars upon their spring mountings, the bars will successively engage and at the time of engagement of the lowermost bar with the body of the person this bar will be moving upwardly so that the tendency is to elevate the body of the person engaged and throw the body against the screen formed by the vertical and transverse members 23 and 25. Arms outthrown in a natural attempt to grasp some supporting surface will very probably come in contact with some portion of this network, particularly the bows 26 thereof by means of which the person may support himself, thus preventing him from falling from the oscillator upon the ground where he would be subject to contact by the wheels of the vehicle. This oscillator is held in any position where it may be forced by collision due to the engagement of the ratchet teeth 38 with the headed members 39, proper engagement being insured by the spring 40.

Where the cars to which fenders of this

type are applied are provided with a starting crank which is not removable, as is the case with at least one well known type of vehicle, a folding starting crank 41 is preferably provided, this starting crank having an extension section 42 to which the cranking portion 43 proper is pivoted. This section 42 extends to the front face of the network formed by the members 23 and 25 and the hinged connection is such that the cranking portion 43 may be either moved into alignment with this extension section or at right angles thereto, at which time it lies against the face of the network and may be secured thereto. A locking pin 44 is provided for locking the sections of the crank in aligned position during the cranking operation.

A structure such as above described may be made very light in weight and at the same time will very efficiently prevent injury to persons with which a vehicle to which it is applied may come in contact. It may be readily applied to the vehicle and will not interfere in any manner with the operation thereof. It will, of course, be understood that this structure is capable of a certain range of change and modification necessary in its adaption to various types of vehicles and I accordingly do not limit myself to such specific structure as hereinbefore set forth except as hereininafter claimed.

I claim:

1. In a guard fender for automobiles, a rigid bar supported from the forward end of the vehicle and in advance of the vehicle, a reticular structure supported from the bar and extending upwardly therefrom, the sides and upper end of the structure being yieldably supported, said structure comprising transverse and vertical members interwoven with one another, vertical supports extending upwardly at the sides of the structure, the transverse members having bowed end portions secured to said supports and extending forwardly in advance of the supports, said transverse members being formed of resilient material.
2. In a guard fender for automobiles, a rigid bar supported from the forward end of the vehicle and in advance of the vehicle, a reticular structure supported from the bar and extending upwardly therefrom, the sides and upper end of the structure being yieldably supported, said structure comprising transverse and vertical members interwoven with one another, vertical supports extending upwardly at the sides of the structure, the transverse members having bowed end portions secured to said supports and extending forwardly in advance of the supports, said transverse members being formed of resilient material, the upper ends of said vertical supports being connected by a cross

bar, springs connecting the upper ends of the vertical members to said cross bar.

3. In a guard fender for automobiles, a rigid bar supported from the forward end of the vehicle and in advance of the vehicle, a reticular structure supported from the bar and extending upwardly therefrom, the sides and upper end of the structure being yieldably supported, said structure comprising transverse and vertical members interwoven with one another, vertical supports extending upwardly at the sides of the structure, the transverse members having bowed end portions secured to said supports and extending forwardly in advance of the supports, said transverse members being formed of resilient material, the upper ends of said vertical supports being connected by a cross bar, springs connecting the upper ends of the vertical members to said cross bar, and braces extending between the upper end of the reticular structure and the vehicle at points spaced from the forward end thereof.

4. In a guard fender for automobiles, a rigid bar supported from the forward end of the vehicle and in advance of the vehicle, a reticular structure supported from the bar and extending upwardly therefrom, the sides and upper end of the structure being yieldably supported, a structure pivoted at its lower end to said cross bar and capable of a limited swinging movement on said cross bar permitting movement of the free ends toward the reticular structure but preventing their return movement, and resilient bumper elements forming a portion of said structure and moving upwardly during movement of the end of the structure toward said reticular structure.

5. In a guard fender for automobiles, a rigid bar supported from the forward end of the vehicle and in advance of the vehicle, a reticular structure supported from the bar and extending upwardly therefrom, supports for the reticular structure at the sides thereof, a plurality of arms pivoted beneath said bar and extending upwardly and outwardly therefrom, a connection between the supports of the reticular structure and the upper ends of certain of said arms permitting movement of the arms toward the supports but preventing return movement thereof, a plurality of bars spring connected to each of said arms, said bars extending transversely of the vehicle and in advance of the arms, and connections between the last named bars maintaining the same in spaced relation.

6. In a guard fender for automobiles, a rigid bar supported from the forward end of the vehicle and in advance of the vehicle, a reticular structure supported from the bar and extending upwardly therefrom, supports for the reticular structure at the sides thereof, a plurality of arms pivoted beneath

25 said bar and extending upwardly and outwardly therefrom, a connection between the supports of the reticular structure and the upper ends of certain of said arms permitting movement of the arms toward the supports but preventing return movement thereof, comprising links pivoted to the last named arms and having slots, headed elements carried by said supports and extending 30 through the slots of the links, one wall of the slot being in the form of a ratchet having forwardly facing teeth, and springs connected with said links and maintaining the toothed face of the links in engagement 35 with said headed elements.

7. In a guard fender for automobiles, a rigid bar supported from the forward end of the vehicle and in advance of the vehicle, a reticular structure supported from the 20 bar and extending upwardly therefrom, supports for the reticular structure at the

25 sides thereof, a plurality of arms pivoted beneath said bar and extending upwardly and outwardly therefrom, a connection between the supports of the reticular structure and the upper ends of certain of said arms permitting movement of the arms toward the supports but preventing return movement thereof, a plurality of bars spring connected to each of said arms, said bars extending transversely of the vehicle and in advance of the arms, and connections between the last named bars maintaining the same in spaced relation comprising members formed of 30 spring material and secured at opposite ends to adjacent bars, said members intermediate their ends being formed to provide spring loops.

35 In testimony whereof I hereunto affix my signature.

ROBERT OSTERHORN.
